UNITED STATES PATENT OFFICE.

IVAN L. EASTMAN, OF TOLEDO, OHIO, ASSIGNOR OF ONE-HALF TO LE ROY E. EASTMAN,
OF TOLEDO, OHIO.

OIL CONCENTRATOR.

Application filed June 18, 1926. Serial No. 116,912.

My invention has for its object to provide a means for removing liquids from the oil contained in an internal combustion engine to thereby restore its viscosity and its efficiency during its use. Thus my invention provides a means for maintaining the oil in its proper lubricating state while it is being used for lubricating the parts of the engine. As is well known, the fuel which is drawn into the cylinders of the engine will pass by the piston rings and enter the engine casing which acts as a reservoir for the oil. The gasoline thus mixed with the oil thins the oil so as to prevent the maintenance of an oil film between the bearings of the engine. Also moisture will enter the chambers in which the oil is contained or through which it passes, such as, the engine casing, the valve chamber etc., which, in the operation of the moving parts of the engine, tends to form an emulsion, particularly, in the presence of foreign solid materials, that reduces the efficiency of the oil as a lubricant. By my invention the lighter hydrocarbons and the moisture is evaporated and drawn through intake of the engine into the engine cylinders where, in the case of hydrocarbons, it is burnt, and, in the case of moisture, it is evacuated through the exhaust. The invention may be contained in structures that vary in their form and to illustrate a practical application of the invention, I have selected two different forms of devices containing my invention as examples of such structures and shall describe them hereinafter. The structures selected are shown in the accompanying drawings.

Figure 1 illustrates a side view of an engine, a part of the engine being shown broken away to illustrate a view of a part of a section of the device containing my invention. Fig. 2 illustrates a longitudinal section of one form of my device. Fig. 3 illustrates a section taken on the plane of the line 3—3 indicated in Fig. 2. Fig. 4 illustrates a transverse section of a modified form of construction that also embodies my invention.

The device containing my invention is located in the bottom of the crank shaft casting 1 of the engine 2, substantially as shown in Fig. 1. The device 3 has a plate 4 that is so located as to cover the oil contained in the casing and so as to be located slightly above the level of the oil. The plate

4 is preferably dished slightly in order to gather the oil that drips or is splashed or thrown from the moving parts of the engine located in the casing and above the plate. The plate is provided with one or more tubes 5 that are located at a point therein such that it will direct the oil, that is collected by the dished plate, to the oil body located below the plate. The tube 5 extends to a point well below the surface of the oil contained in the bottom of the crank shaft casing of the engine.

Means is also provided for producing a vacuous condition above the level of the oil and below the plate 4. This may be done by means of a pipe 6 which is connected at one end to the intake manifold 7 of the engine and at the other end to the plate 4. In the form of construction shown a thimble or dime 8 is connected to the plate 4 and the end of the pipe 6 terminates in the top of the thimble 8. This is to prevent the oil from entering into the pipe 6 and being drawn into the intake manifold of the engine. Owing to the vacuous condition that is created within the space confined by the level of the oil and the plate 4 air will be drawn through the tube 5 which passes through the oil and thus aerates the oil. This will cause evaporation of the lighter hydrocarbons that may work by the piston rings and enter the oil chamber and also evaporate any moisture that may enter the engine casing through the breather valve or that may be produced in the firing of the cylinders and which passes the piston rings into the engine casing. The rate of evaporation will increase as the temperature of the engine rises which occurs when the engine has been running for a material length of time. The lighter hydrocarbons and the moisture will be drawn through the pipe 6 into the intake manifold and will pass with the carbureted fuel into the engine cylinders. The fluids thus drawn from the oil of the engine will be utilized with fuel in the operation of the engine or will be discharged through the exhaust.

The device containing my invention may be made in the form of a pan having a dished or pyramidal bottom, and a flange 10 that may correspond to the configuration of the lower side of the interior of the engine casing. In this form of construction the pan is inverted and preferably has dimen- 110

sions substantially the same as that portion of the engine casing that forms the reservoir for the oil. It may be made somewhat smaller, provided it has a volume sufficient to contain the oil of the engine casing and sufficient additional space containing air at a pressure below atmospheric and thereby prevent the movement of the oil into the pipe 6. In the form of construction shown in Fig. 4 the edges of the plate 11 substantially fit the engine casing so as to substantially prevent the admission of a material amount of air between the edges of the plate and the side walls of the engine casing. If desired the plate 11 may be made integral with the engine casing or may be securely fitted in position.

The oil is drawn by a suitable pump, such as the pump indicated at 12, through the pipe 13 and is delivered to the bearings of the engine in the manner well known in the art. The crank shaft casing thus forms a reservoir for the oil from which it is drawn and delivered to the bearings of the automobile and in which it is maintained at a uniform concentration or consistency to produce a constant lubricating efficiency that will insure long life to the engine. By "crank shaft casing" it is intended to include and refer to that portion, or those portions, of the engine commonly used for containing or storing the engine lubricating oil.

I claim:

1. In an oil concentrator for internal combustion engines, a plate extending across the crank shaft casing for covering the oil in the casing, means for producing a vacuous condition below the plate, a tube extending from the plate to a point below the level of the oil for directing air through a portion of the oil.
2. In an oil concentrator for internal combustion engines, a plate extending across the crank shaft casing for covering the oil in the casing, means for producing a vacu-

ous condition below the plate, a tube extending from the plate to a point below the level of the oil for directing air through a portion of the oil, the plate having sloping portions extending to the tube for directing the oil to a point below the plate. 50

3. In an oil concentrator for internal combustion engines, a plate extending across the crank shaft casing for covering the oil in the casing, means for producing a vacuous condition below the plate, a tube extending from the plate to a point below the level of the oil for directing air through a portion of the oil, the plate having flanges located 60 at its edges extending to a point below the level of the oil. 65

4. In an oil condenser for internal combustion engines, a flanged plate extending across the crank shaft casing and located a short distance above the level of the oil in the casing, the flanges of the plate extending below the level of the oil and the plate having a tube extending to a point below the level of the oil, the plate being inverted 70 pyramidal the tube located at the apex of the pyramidal form, means for producing a vacuous condition between the level of the oil and the underside of the plate whereby oil will be collected by the plate and fed into the portion of the crank shaft casing below the plate and air will be directed through a portion of the oil within the crank shaft casing. 75

5. In an oil concentrator for internal combustion engines, a partitioning member forming a chamber in the lower part of the crank shaft casing of the engine and located above the level of the oil in the casing, the chamber having an inlet for air located below the level of the oil in the chamber, a pipe communicating with the top of the chamber for drawing air from the top of the chamber. 80

In testimony whereof I have hereunto signed my name to this specification.

IVAN L. EASTMAN.
